UNDERWATER SEARCHLIGHT

Jack Birns, Los Angeles, Calif., assignor to Birns & Sawyer Cine Equipment Co., Inc., Los Angeles, Calif., a corporation of California

Filed Feb. 14, 1969, Ser. No. 15,778

Term of patent 14 years

Int. Cl. D26—02

U.S. Cl. D48—20

FIGURE 1 is a side elevational view of an underwater searchlight, showing my new design; the other side, not shown, is the mirror image thereof;

FIGURE 2 is a front end elevation view thereof;

FIGURE 3 is a rear end elevational view thereof; and
FIGURE 4 is a perspective view thereof.

The broken line showing of a mounting yoke in FIGURE 4 is merely for illustrative purposes.

I claim:

The ornamental design for an underwater searchlight, substantially as shown and described.
